UNITED STATES PATENT OFFICE.

EDWARD M. LANE, OF CHARLESTON, SOUTH CAROLINA.

MEANS FOR FORMING CONCRETE BLOCKS.

Application filed February 13, 1924. Serial No. 692,596.

To all whom it may concern:

Be it known that I, EDWARD M. LANE, a citizen of the United States, residing at Charleston, in the county of Charleston and State of South Carolina, have invented certain new and useful Improvements in Means for Forming Concrete Blocks, of which the following is a specification.

This invention relates to a method and apparatus for use in the manufacture of hollow concrete blocks for building purposes, and more specifically to concrete blocks having faces to simulate brick work.

The present invention may be regarded as in part a further modification of that described and shown in my prior copending application, Serial No. 659,845, filed August 28, 1923, in which I have disclosed the use of removable strips for forming imitation mortar joints. In such an arrangement, the blocks were formed face down in the mold.

The present invention differs from that shown in the above mentioned application in that I now propose to provide means for forming blocks face up in the mold, and to this end I propose to support the imitation mortar joint forming strips at the top of the mold. A further feature of the present invention consists in a method of forming notches or hollows in the end portions of the blocks, in order to produce structural building elements which readily lend themselves to the desired method of assembling in a wall so that air spaces extending vertically through the wall may be provided, as is usual.

In order that the invention may be readily understood, reference is had to the accompanying drawings, in which:

Figure 1 is a plan view of my improved mold box;

Figure 2 is a side elevation thereof;

Figure 3 is a transverse section thereof on the line 3—3 of Figure 2;

Figure 4 is a plan view showing a modified arrangement of the imitation mortar joint forming strips;

Figure 5 is a perspective view illustrating my improved method of notching the ends of the freshly formed blocks; and

Figure 6 is a perspective view showing the appearance of a finished block.

Referring to the drawings in detail, and particularly to Figures 1, 2 and 3 thereof, my improved mold box is similar in con-

struction to that shown in my prior copending application, above referred to. The box comprises a bottom 1, side walls 2 and 3, hinged to the bottom at 4, and end walls 5 hinged to the ends of the rear side wall 3, 60 by means of hinges 6. The walls and bottom of the box are held together in operative position, as shown in the drawings, by means of latches or fasteners 7 of any suitable or desired type.

A pair of openings 8 are formed in the front wall 2, in order to receive cores 9. These cores preferably comprise perforated sheet metal containers having one end integral therewith, as indicated at 10, and the 70 other end closed by means of a plug or block 11. These containers, filled with sand or other absorbent material, are inserted through the openings 8 and are supported in horizontal position within the box by 75 means of pins 12, secured thereto and entering aligned openings 13 and 14, formed in a pallet board 15 and the rear wall 3, respectively.

The imitation mortar joint forming strips comprise, in the embodiment illustrated, a long central strip 16 extending from end to end of the mold box, and supported in notches 5^a, formed in the extreme upper edges of the end walls 5. Detachably connected with the strip 16, as by means of dowel pins 18 or the like, are a series of shorter transversely extending strips 17, suitably spaced in staggered relation, and supported at their outer ends in notches 19 85 and 20, formed in the upper edges of the pallet board 15 and the side walls of the box respectively.

Other absorbent cores 21, preferably comprising perforated sheet metal containers 95 filled with sand, are located in two corners of the box, as shown in Figure 1, and the upper edges of these cores are recessed or notched, as shown at 22 to receive the strip 16.

In using the above described box for forming blocks, a layer of paper or the like is first preferably placed on the bottom, to prevent sticking. The absorbent cores being in position as shown, wet concrete is then deposited in the box until within a short distance of the top. Then, a special mixture for the ornamental face is applied, and filled in between and around the strips 16 and 17. The filled box is then preferably 110

subjected to vibration, as by means of any well known jogging table or device; and, after a few minutes, the water has been sufficiently absorbed by the cores 9 and 21 to permit the cores 9 to be withdrawn and the mold box to be opened up and the block turned over on its side, resting upon the pallet board, as shown in dotted lines in Figure 3. The strips 16 must, of course, be removed before the box is opened and the block turned over.

As illustrated in Figure 1, the strips 16 and 17 are separable from each other and may be independently removed one at a time, being preferably withdrawn endwise to prevent mutilating the grooves in the concrete.

In some cases, however, I may rigidly and permanently attach all of the strips together. This is shown in Figure 4, in which 16^a represents the longitudinally extending strip and 17^a the transversely extending strips. These latter are rigidly secured to the strip 16^a, as by means of T-plates 23 or by other suitable means. When using the strips constructed as in Figure 4, the entire set is, of course, lifted vertically out of the notches in the upper edges of the box, when it is desired to remove the same.

In order to form hollows or notches in the ends of the blocks to facilitate formation of air spaces when the blocks are assembled in a wall, I follow the method illustrated in Figure 5. Referring to this figure, the block is shown as it appears when removed from the mold and resting upon the pallet board 15. The block comprises a lower row of brick faces *a* and an upper row *b*, separated by an imitation mortar joint *c* formed by the strip 16, the bricks themselves in each row being separated by imitation mortar joints *d* formed by the strips 17. The cavities or openings *e* extending vertically through the center of the block are formed by the cores 9, while the stepped ends *f* are formed by the cores 21.

As above stated, when the block is removed from the mold, it is still in a green or soft condition, and is resting upon the pallet board 15. As soon as it is removed from the mold, I place in the stepped portion *f*, at the end thereof, a block or template A, having a recess or notch B, formed in one edge thereof. This notch or recess is illustrated in Figure 5 as being semi-circular in shape, but any desired profile may, of course, be employed. I also provide a cutting implement in the nature of a scoop C, preferably formed of sheet metal and provided with a handle D, such scoop conforming with the shape of the profile of the recess B in the template. After the template has been placed in position, as shown, the scoop or cutter C is laid against the inner face of the recess B and moved verti-

cally down toward the pallet board, thus cutting through the soft concrete and scooping out or removing a portion *x* thereof along a line corresponding to the profile of the recess B and the shape of the tool.

In Figure 6, I have illustrated the finished block in which the notch or hollow formed in its end by the above described method is shown at *g*. As above mentioned, this notch may be either semi-circular, as shown, or rectangular, so as to conform in shape with the openings *e*. I have found that this method of cutting or scooping out the ends of the blocks, while still soft, by means of a template and special tool, can be done easily and rapidly and is preferable to attempting to form such notches by means of a core inserted in the mold box.

In some cases, after the requisite experience, a skilled operator will be able to use the scoop C alone, without the necessity of a template, and will be able to make a cut of sufficient accuracy by manually positioning the tool. This, of course, is easier and quicker, and where such "free hand" method is employed, the number of blocks which an operator can turn out in a day is considerably increased.

What I claim is:

1. The combination with a horizontal open top mold box for making building blocks having a face to simulate brick work, of a removable strip disposed at the top of the box to form an imitation mortar joint in the exposed face of the block, the upper edges of two opposite walls of the box having notches in which said strip is supported and by means of which it is positioned.

2. The combination with a horizontal open top mold box for making building blocks having a face to simulate brick work, of a set of removable strips disposed at the top of the box to form imitation mortar joints in the exposed face of the block, the upper edges of the walls of the box having notches in which said strips are supported and by means of which they are positioned.

3. The combination with a horizontal open top mold box for making building blocks having a face to simulate brick work, of a set of removable strips disposed at the top of the box to form imitation mortar joints in the exposed face of the block, the upper edges of the walls of the box having a series of notches formed therein, one of said strips resting at both ends in said notches and being wholly supported thereby, and others of said strips resting at one end in one of said notches, and being supported at their other end by said first strip.

4. The combination with a horizontal open top mold box for making building blocks having a face to simulate brick work, of a set of removable separable strips dis-

posed at the top of the box to form imitation mortar joints in the exposed face of the block, the upper edges of the walls of the box having a series of notches formed therein, one of said strips resting at both ends in said notches and being wholly supported thereby, and others of said strips resting at one end in one of said notches, and detachably engaging at their other end said first

10 strip.

5. The combination with an open top mold box for making concrete blocks having a face to simulate brickwork, said box

having a bottom and sides, of a vertical pallet board disposed inside the box, adjacent 15 one of the side walls thereof, and a removable strip disposed at the top of the box to form an imitation mortar joint in the exposed face of the block, the upper edges of said pallet board and side wall having registering notches in which said strip is supported, and by means of which it is positioned.

In testimony whereof I affix my signature.

EDWARD M. LANE.
